UNITED STATES PATENT OFFICE.

JOHN B. GENIN, OF ST. ALBANS, VERMONT.

COMBINATION CLUTCH-COUPING FOR PIPES.

SPECIFICATION forming part of Letters Patent No. 429,126, dated June 3, 1890.

Application filed December 31, 1889. Serial No. 335,555. (No model.)

To all whom it may concern:

Be it known that I, JOHN B. GENIN, a citizen of the United States of America, and a resident of the city of St. Albans, in the county 5 of Franklin and State of Vermont, have invented certain new and useful Improvements in Combination Clutch-Couplings for Pipes, of which the following is a full, clear, and exact description.

This improved coupling is composed of two tubular sections to be butted end to end, and each suitably adapted for attachment to a section of the pipe to be coupled together, two tongue projections, one mounted on or carried by each coupling-section and both shaped to lap over the joints of the coupling-sections and to extend lengthwise of and to surround the coupling-section butted against the section which carries it, and each having in one 15 edge of its overlapping portion a lateral notch, in combination with radial studs or pins, one on each coupling-section, and each in position when the coupling-sections are butted to engage the notch of a tongue projection, and 20 springs, one on each coupling-section and arranged to press laterally on the edge of a tongue projection carried by the opposite coupling-section, and thereby to engage the notch of said tongue projection with its pin 25 of the opposite coupling-section, and to hold them against accidental disengagement, all substantially as hereinafter described.

In the drawings forming part of this specification, Figure 1 is a side view of the coupling in two sections and the sections butted end to end and a central longitudinal section of the end of one of the sections showing its attachment by loose ring and screw-nut to a hose or pipe. Fig. 2 is a view of the coupling at 35 a side different from that of Fig. 1, as will hereinafter appear. Figs. 3 and 4 are cross-sections on lines 3 3 and 4 4, respectively, Fig. 1. Fig. 5 is a central longitudinal section on line 5 5 of Fig. 1.

In the drawings, A and B are the two similar tubular sections of the coupling of this invention butted end to end, C representing the line of joint.

A^2 and B^2 are two tongue projections, one 45 mounted on or carried by the coupling-section A and the other B^2 mounted on or carried by the coupling-section B. Each tongue

projection A^2 B^2 of the coupling-sections A B laps over the joint C between them, and extends over and partially surrounds the 55 coupling-section adjoining that which carries it, and the edges a and b of the tongue projections A^2 B^2 , respectively, and at their overlapping portions, as stated, have each a lateral notch A^3 B^3 , respectively, for engagement 60 therewith of a radial stud or pin A^4 B^4 respectively of the coupling-sections A B.

A^5 B^5 are bent springs, one held on each coupling-section A B, respectively, and each arranged to press laterally on the edge a^2 or 65 b^2 of the tongue projection A^2 or B^2 of the opposite coupling-section, and the edges a^2 b^2 are in each instance on an edge of the tongue projection opposite to its notched edge a b . On placing the coupling-sections together end 70 to end the tongue projections A^2 B^2 , passing over the sections, are finally, with the ends of the sections, butted in engagement by their notches A^3 B^3 with their respective pins A^4 B^4 of the sections, being brought thereto by 75 the action of the bent springs A^5 B^5 , which continue to hold them engaged against accidental disengagement, while allowing them to disengage on sufficient force being applied to draw the coupling-sections apart. The coupling-sections A and B have also each a tongue projection D^2 E^2 , respectively lying when the sections are united between the edges of the tongue projections A^2 B^2 , that are not in engagement, and serving in conjunction with 80 the latter projections as guides in placing together and drawing apart the coupling-sections. The tongue projections described may be integral with their respective coupling-sections or separate from them and suitably 85 attached. Again, the springs A^5 B^5 may be rigidly attached to their respective coupling-sections; but it is preferable to confine each between opposed fixed bearings f^2 with a set-screw g , as they then can be adjusted in their 90 spring action.

The coupling-sections at their ends opposite to their butted ends, as described, have each a male screw-thread F and a conical end or nipple G. H H are screw-nuts screwing on 100 the screw-threaded ends F of the coupling-sections, and each contains a loose ring J, which is engaged by its internal annular shoulder or flange K, and surrounds a hose

or pipe L, otherwise entered upon the conical end of the coupling-section and into the screw-nut, and by screwing the latter onto the coupling-section the hose or pipe is fastened to it, 5 all as is obvious without further explanation.

The loose ring J makes the bearing for the screw-nut on the hose or pipe, and thus twisting of the hose or pipe from turning the nut is obviated.

10 This invention is more particularly designed for coupling the pipes of railway-cars employing the air system for braking the cars or a system for heating cars by steam from the locomotive-boiler or other generator 15 of the train; but it is not to be limited in any regard thereto.

Having thus described my invention, what I claim, and desire to secure by Letters Patent, is—

20 1. A coupling in sections A B, butted end to end, and each having tongue projections A² B² lapping over the joint C of and fitting the sections and having lateral notches A³ B³, in combination with radial pins A⁴ B⁴ and 25 springs A⁵ B⁵ of the coupling-sections, the

former to engage the notches of the tongue projections and the latter to press laterally on the tongue projections to secure said engagement, substantially as described, for the purpose specified.

2. A coupling in sections A B, butted end to end, and each having tongue projections A² B² D² E² lapping over the joint C of and fitting the sections, and the tongue projections A² B² having lateral notches A³ B³, in combination with radial pins A⁴ B⁴ and springs A⁵ B⁵ of the coupling-sections, the former to engage the notches of the tongue projections and the latter to press laterally on the tongue projections to secure said engagement, substantially as described, for the purpose specified.

30 In testimony whereof I have hereunto set my hand in the presence of two subscribing witnesses.

JOHN B. GENIN.
